UNITED STATES PATENT OFFICE.

WALTER E. MOULTON, OF PLAIN CITY, OHIO.

TOP-NOTCH FOR UMBRELLAS.

No. 904,349.

Specification of Letters Patent.

Patented Nov. 17, 1908.

Application filed February 28, 1908. Serial No. 418,349.

To all whom it may concern:

Be it known that I, WALTER E. MOULTON, a citizen of the United States, residing at Plain City, in the county of Madison and 5 State of Ohio, have invented certain new and useful Improvements in Top - Notches for Umbrellas, of which the following is a specification.

My present invention pertains to improvements in top-notches for umbrellas, the construction and advantages of which will be hereinafter set forth, reference being had to the annexed drawings, wherein:

Figure 1 is a longitudinal sectional view 15 of an umbrella-staff or stick, with the top-notch applied thereto; Fig. 2 a side elevation of the top-notch, a portion of the staff and several of the ribs; Fig. 3 is a sectional view, taken on the line 3—3 of Fig. 2; 20 Fig. 4 is a side elevation showing the movable member of the notch so arranged with relation to the fixed member that a rib may be removed or inserted; Fig. 5 a transverse sectional view, on the line 5—5 of Fig. 4; 25 Fig. 6 a similar view, on the line 6—6 of Fig. 4; and Fig. 7 a perspective view of the spring employed to hold the movable member against rotation when the parts are in one position and to support the movable 30 member but permit its rotation with reference to the fixed member and the staff when it is desired to remove or insert a rib.

The main object of the present invention is to provide a simple and efficient top-notch, 35 in which a rib may be inserted or removed without the necessity of taking off the cover and the finishing or rain cap usually employed to hold the cover in position.

A further object of the invention is to so 40 construct the top-notch that the movable member thereof may be removed bodily from the fixed member, thereby permitting all of the ribs to be taken out; or it may be rotated about the staff and beneath the fixed 45 member so that one rib at a time may be inserted or removed.

A still further object of the invention is 50 to provide a spring of special form which will normally hold the movable member in its elevated position but permit rotation thereof about the staff, so that a particular rib may be brought into alinement with a slot formed in the fixed member and through which the rib is removed.

With these and other objects in view, a description of the invention will now be given.

In the drawings, A denotes the staff, preferably formed as a hollow metallic tube and having secured thereto, by means of a rivet B, the fixed member of the retainer, formed 60 with a sleeve or collar portion C and a body portion D, which extends outwardly at the lower end of the collar C. The upper face of the body portion, as will be seen upon reference to Figs. 1, 2 and 4, is curved downwardly so as to form a fair bearing for the cover and the rain or finishing cap, which are secured in place thereon, but which are not shown in the drawings, as they form no part of the present invention.

A slot E is provided in the body portion of the fixed member, the slot being of sufficient size to permit the headed end F of one of the ribs G to be passed therethrough. The body portion will likewise be made of 75 such thickness that when the head F is introduced into the slot E it will not be necessary to remove the cover in order to permit its entrance.

Mounted upon the staff below the fixed 80 member is a second member, having a sleeve portion H and a body portion I, the latter being provided with a series of vertically-disposed slots J. Adjacent to the inner portions of the slots are formed seats or sockets 85 to receive the heads F of the ribs. A slot K is formed in the lower end of the sleeve H, said slot, when the parts are in their normal positions, receiving the shouldered portion L formed upon the upper or headed end of a 90 spring M. Said spring, as will be noted, is provided with a tongue or upward extension N which, when the parts are in their normal position, or that shown in Figs. 1 and 2, extends into a slot O formed in the staff, the 95 shouldered portion or head of the spring passing through the slot and through slot K just referred to. The head is likewise provided with a second shoulder P, located at a point below the shoulder L which, when the 100 spring is moved inwardly or to the position shown in Figs. 4 and 6, passes beneath the lower edge of the sleeve H and sustains the movable member of the notch, while permitting rotation of said member with reference 105 to the staff and the fixed upper member of the top-notch. The spring M is also provided at a point adjacent to its lower end

with an ear Q, and by reason of the curvature of the spring the lower end bears against the opposite side of the staff.

When the parts are in their normal positions, the tongue N of the spring extends into the slot O and the spring cannot be displaced or become twisted, as some portion of it always extends into the slot. Thus, for instance, when the spring is pushed back 10 and the shoulder P stands beneath the lower end of the sleeve H, the head of the spring, or that portion below the shoulder P still extends through the slot O, as shown in Fig. 4, and the spring is thus held against any 15 twisting movement. If it be desired to lower the movable member, it is necessary to push the spring inward, so that the lower portion of the head stands within the slot. It will still, however, have a bearing in the slot O 20 and is thus prevented from becoming displaced. It is not necessary, with the spring shown, that a hole be bored in the tube to receive the lower end of the spring, nor to pass a rivet through the spring in order to 25 hold it in position. In case it should be desired to remove one of the ribs, the spring is pushed inwardly until the shoulder P stands beneath the lower edge or in line with the lower edge of the sleeve portion H. The 30 staff and the fixed member of the top-notch or retainer may then be rotated with reference to the movable member; or, by holding the staff rigid and taking hold of the ribs, the movable member with the ribs may be 35 rotated about the staff until such time as the particular rib which it is desired to remove stands in alinement with the slot E. By then elevating the rib-end the head F will 40 pass into the slot E and may be withdrawn therefrom, to be repaired or replaced by a new rib. As before noted, it is not necessary to remove the finishing cap or cover in order 45 to effect the removal of the ribs. In fact, the cover need not be disturbed at all, which is a point of manifest advantage.

This construction does away with the necessity of slotting both the upper and lower members of the top-notch, thus saving considerable expense and also affording a smooth 50 surface upon which the cover may bear.

By reason of the fact that the upper member presents an unbroken surface, except for the single opening or notch E, it acts to keep the water from passing into the bearings for 55 the rib-ends. Furthermore, by having the slot for the removal of the ribs formed in the upper member, the structure is in no sense weakened while, as above noted, it is necessary to slot but one member only.

Having thus described my invention, what 60 I claim is:

1. In combination with an umbrella-staff, a member fixed thereto, said member presenting a substantially unbroken face except 65 for a slot or opening formed in its side of a

size sufficiently large to permit the entrance and withdrawal of a retaining head formed upon a rib; a second member loosely mounted upon the staff beneath the fixed member, said second member being provided with a series of radially-disposed slots adapted and designed to receive heads formed upon the ends of the ribs; and a spring mounted within the staff, said spring projecting outwardly beneath the movable member and 70 serving to hold the same in an elevated position. 75

2. In combination with an umbrella-staff, a member fixed thereto, said member being provided with an outwardly-projecting, downwardly-inclined substantially unbroken face, and having a notch or recess formed in the edge thereof, the body of the member being of such dimensions as to permit a rib-end to be introduced into and withdrawn from said notch without affecting the cover which normally rests upon the inclined face; a second member mounted upon the staff below the fixed member, said second member being provided with a series of radially-disposed slots and sockets formed in the inner portions of the slots to receive the headed ends of the ribs; and a spring mounted within the staff and serving normally to hold said second member against movement. 95

3. In combination with an umbrella-staff, a member secured thereto, said member being provided with an outwardly-extending, downwardly-inclined substantially unbroken upper face adapted to receive an umbrella-cover and being likewise provided with a notch or recess in its outer edge into and from which a rib-end may be inserted and withdrawn; a second member mounted upon the staff below the fixed member, said second member being provided with a series of radially-disposed slots and sockets formed in the inner portions of said slots to receive the rib-ends; and a spring mounted within the staff, said spring being provided with a head having two outwardly-projecting shoulders, said head and shoulders passing through a slot formed in the staff and the upper shouldered portion passing into a slot formed in the lower portion of the movable member and serving, when thus positioned, to hold the movable member in its elevated position and against rotary movement. 100 105 110 115

4. In combination with an umbrella-staff, a member fixed thereto, said member being provided with an outwardly-extending, downwardly-inclined upper face which is substantially continuous throughout, and with a notch or recess formed in its edge, 120 said notch being of a depth sufficient to permit a rib-end to be introduced into and withdrawn therefrom; a second member mounted upon the staff below the fixed member, said second member being provided with 125 130

a series of radially-disposed slots and sockets formed to receive the ends of the ribs, and with a notch in its lower edge, said notch being out of alignment with the adjacent radially-disposed slots; and a spring mounted within the staff and provided with a head which normally projects through a slot formed in the staff, the slot being in alignment with the notch or recess formed in the fixed member, said spring likewise being provided with a head which projects into the notch formed in the lower portion of the second member and thereby holds the same in its elevated position and against rotation, 15 with its radially-disposed slots out of alignment with the notch or recess formed in the fixed member.

5. In combination with an umbrella-staff, a member fixed thereto, said member being provided with a notch or recess in its edge to permit the entrance and withdrawal of a rib-end the upper face of said member being otherwise unbroken; a second member mounted upon the staff below the fixed member, 20 said second member being provided with a series of radially-disposed slots and sockets formed in the inner portions thereof to receive the rib-ends, and being likewise provided with a notch in its lower edge; and 25 a spring mounted within the staff, said spring being provided with a head adjacent to its upper end and with a tongue extending from said head, said tongue and head normally projecting into a slot formed in the staff, the headed portion of the spring being provided with two shoulders extending outwardly therefrom in different horizontal planes, the uppermost shoulder standing normally in the notch in the lower 30 portion of the second or movable member and serving to hold said member against rotation and downward movement, and the second shoulder serving, when the spring is pushed inwardly, to bear against the under 35 face of the movable member and prevent its downward movement while permitting rotation of said member about the staff, whereby

any rib may be brought into alignment with the notch or recess formed in the fixed member to permit withdrawal of such rib. 50

6. In combination with an umbrella-staff, a member fixed thereto, said member presenting a substantially unbroken upper face and being provided with a notch or recess in its outer edge, the body of the member 55 being of sufficient depth to permit the positioning of a rib-end in the notch without projecting above the upper face of the member; a second member mounted upon the staff below the fixed member, said second 60 member being provided with a series of radially-disposed slots and sockets formed in the inner portions thereof to receive the rib-ends, and likewise provided with a notch or recess in its lower edge; a spring mounted 65 within the staff, said spring being curved or bow-shaped and having an ear projecting outwardly therefrom adjacent to its lower end and adapted to bear upon the wall of the staff opposite that against which the 70 lower end bears; a head formed upon the spring; and a tongue extending upwardly from the head, said tongue and head normally passing into a slot formed in the staff and the head having two outwardly-projecting 75 shouldered portions, the upper shouldered portion normally standing in the notch or recess formed in the lower portion of the movable member, and holding the same in its elevated position and against 80 rotation, while the second outwardly-extending shouldered portion serves, when the spring is moved inwardly to a slight extent, to bear against the under face of the movable member and to hold it against downward movement, while permitting rotation 85 thereof about the staff.

In testimony whereof I have signed my name to this specification in the presence of two subscribing witnesses.
